UNITED STATES PATENT OFFICE.

BRUNO V. NORDBERG, OF MILWAUKEE, WISCONSIN, ASSIGNOR TO THE
BRUNO NORDBERG COMPANY, OF SAME PLACE.

CUT-OFF GEAR FOR STEAM-ENGINES.

SPECIFICATION forming part of Letters Patent No. 394,501, dated December 11, 1888.

Application filed August 3, 1888. Serial No. 281,869. (No model.)

To all whom it may concern:

Be it known that I, BRUNO V. NORDBERG, of Milwaukee, in the county of Milwaukee, and in the State of Wisconsin, have invented certain new and useful Improvements in Automatic Cut-Off Gear for Steam-Engines; and I do hereby declare that the following is a full, clear, and exact description thereof.

My invention relates to automatic cut-off gear for steam-engines, and will be fully described hereinafter.

In the drawings, Figure 1 is a vertical section of a cut-off gear embodying my invention. Fig. 2 is a side elevation of the same. Fig. 3 is an enlarged section of the upper portion of my gear. Fig. 4 is a rear elevation. Fig. 5 is a section on line 55, Fig. 4, and Fig. 6 is a detail of a modification.

A is the stand that contains the valve and cut-off.

B is the rock-shaft, that, through crank C, is connected to the eccentric-rod of the engine. This rock-shaft has one bearing in the stand at a and the other in a sleeve, b, that is fitted in a housing, b'. Just opposite shaft B another shaft, c, is journaled in the stand, and on shaft B is fixed a carrier, d, while shaft c loosely carries a like carrier, d', and these two carriers are connected at their upper ends by links e e and bolts f f, which latter form the pivots for triggers g, one of which is interposed between the upper arms of each carrier.

D are lifting-levers, one of which turns loosely on shaft B and the other on shaft c, and each lifting-lever is interposed between the lower arms of a carrier, d, and has a notch, d², in its upper corner to receive the lower end of a trigger, g, while its lower end projects under the hanger-bar E of the valve-stem F. Each of the triggers g is weighted, as at g', to insure its engagement at the proper time with its subjacent lifting-lever D, as shown in Fig. 1. The drop of the lower ends of the lifting-levers D is limited by screw-stops J, that project up through flanges j in the stand, and the valve-stem is depressed by a spring, K, as in patent granted me September 6, 1887, No. 369,612.

L is the governor-stem, the lower end of

which rests on the upper end of a sliding rod, 50 M, which in turn terminates in a concaved head, m, having ears n, and a double tripping-dog, o, is pivoted in head m so that its ends project under ears n in position to receive adjusting-screws p, by which it is set.

The upper end of the stem L has a cap, P, screwed onto it, and this cap has a bolt, q, projecting up from its center into a cup, R. The bolt q is shouldered to form a seat for the cup R, and is also reduced and screw-threaded 60 to receive a nut, r, that secures the cup R on the seat formed by so reducing it; but before the cup is placed on the bolt q a clutch, s, is slipped on said bolt, and this clutch rests on cap P and has side openings in which the 65 short arms Q, that form part of the governor-arms Q', fit.

T is a cap that is screwed onto the upper end of the sleeve U, that carries the governor-arms, and this cap is formed with a hollow 70 plunger, u, that fits in the cup R. The screw-threaded boss of a needle, V, is passed down through the hollow in plunger u, which has side openings, w, that communicate with cup R through the plunger.

The rod M is slotted at m' to receive one end of a lever, m², that is pivoted to the stand at m³, and the outer end of this lever, which is weighted, is suspended by a cord, h, from the arm h' of a sleeve, h², of the sleeve h³, that 80 forms the bearing of the driving-shaft h⁴ of the governor, which shaft h⁴ is connected by bevel-gearing h⁵ h¹⁰ with a sleeve, H, that carries the governor-sleeve U. The sleeve h² has an arm, h⁶, in which the stud of a pinion, h⁷, 85 revolves, and this pinion carries the pulley of the belt X, that connects the governor with the engine, and also meshes with a pinion, h⁸, on shaft h⁴. The operation of this portion of my device does not differ materially in operation from that in patent granted me September 6, 1887, No. 369,611.

While the belt is on and intact it counter-balances the weight h⁹ on sleeve h², and the connection between lever m² and arm h' is 95 slack; but should the belt break or slip off the pulley weight h⁹ will drop and arm h' will lift lever m² and cause its inner end to

depress the rod M and throw the dog o upon the triggers g and disengage them from the lifting-levers.

It will be seen that the trip-lever carries 5 and the lifting-levers have the same axis, and there is no lost motion whatever in triggers g and lifting-levers when they are in engagement, and that their action is certain and noiseless.

10 The cup R is to be filled with oil and serves as a dash-pot to prevent jar from the sudden action of the governor.

In the modification shown in Fig. 6 a hook, 15 g^3 , is substituted for the weight, the effect of which is obtained by a spring, g^2 , one end of which is caught on the hook and the other on bolt J .

Having thus fully described my invention, what I claim as new, and desire to secure by 20 Letters Patent, is—

1. The combination, with the valve and its

hanger or stem, of two lifting-levers independent of each other and of the valve-hanger, two triggers or trip-levers, and carriers therefor oscillating on the same center as the lifting-levers, substantially as and for the purpose set forth. 25

2. The combination, with the trip-levers and lifting mechanism, of the governor and its stem and a sliding rod, and a tripping-dog 30 pivoted to the lower portion of the said rod, and adjusting-screws therefor, substantially as described.

In testimony that I claim the foregoing I have hereunto set my hand, at Milwaukee, in 35 the county of Milwaukee and State of Wisconsin, in the presence of two witnesses.

BRUNO V. NORDBERG.
